UNITED STATES PATENT OFFICE.

ANDREAS FORSTER AND HANS WANEK, OF VIENNA, AUSTRIA-HUNGARY.

CHAIR FOR THEATERS OR THE LIKE.

1,081,034.

Specification of Letters Patent.

Patented Dec. 9, 1913.

Application filed November 7, 1912. Serial No. 729,925.

To all whom it may concern:

Be it known that we, ANDREAS FORSTER, gentleman, and HANS WANEK, gentleman, of Vienna, in the Empire of Austria-Hungary, have invented certain new and useful Improvements in or Relating to Chairs for Theaters or the like; and we do hereby declare the following to be a full, clear, and exact description of the invention, such as will enable others skilled in the art to which it appertains to make and use the same.

This invention relates to seats for theaters or the like of the kind in which both the seat proper and its back can be automatically and positively swung aside out of the position of use when it is desired to form a passage or gangway.

According to this invention an electric incandescent lamp is arranged on the supporting frame to which the seat and the back are pivoted, and a rotary switch is provided in the lamp circuit which is controlled by the movement of the back or of the seat proper in such a manner that the lamp is switched into circuit by such movement. In the event of the main lighting installation failing, these small lamps supply the necessary light and moreover indicate the exits to the public who are thus afforded guidance.

A chair or seat according to this invention is illustrated in the accompanying drawing, in which—

Figure 1 is an elevation, Fig. 2 a vertical section, and Fig. 3 a detail of the chair, showing the electrical connections of the lamp.

To a lateral supporting frame 1 of any desired construction is pivoted the folding seat 2 which, in the position of use, could also rest, if desired, on a rib 3 of the next supporting frame 1. The pivot pin 4 (Fig. 3) of the seat is provided with an arm 5 which by means of the links 6 and 7 engages with the back 8 of the chair, the back like the seat proper being pivoted to the lateral supporting frame. A spring 10 engaging with the arm 9 of the pivot pin of the seat, can effect in the well known manner automatic folding back of the seat, if this is not done by the weight of the back alone.

When the seat 2 is turned into the position of use, and in that way its pivot pin 4

turned, the arm 5 of the latter, by means of the links 6 and 7, will bring about at the same time a turning upward of the back 8. If the seat is released, it will be folded up by the action of the spring 10, the back coming simultaneously into the plane of the lateral supporting frame, so that the gangway at right angles to the line of seats will be quite clear. At the same time, a switch will be operated which will close a circuit in any desired manner and so illuminate an incandescent lamp countersunk in the supporting frame. This switching device may for example consist of an insulated sleeve 11 mounted on the pivot pin 4 (Fig. 3) and comprising a conductive part 12 and a non-conductive part 13. Against this sleeve 11 presses one end of a sliding metal spring 14, the other end of which is connected by means of a conductive wire 15 to the one pole of an electric source 16, having its other pole connected by a wire 17 to the electric incandescent lamp 18. The conductive part 12 of the sleeve also communicates by means of a conductor 19 with the lamp.

When the seat is in its position of use the spring 14 bears against the non-conductive part, so that the electric circuit is interrupted. In case, the seat is released and turned into its vertical position the spring 14 makes contact with the conductive part 12 of the sleeve, thereby closing the circuit, so that the filament of the lamp is brought to incandescence.

What we claim as our invention and desire to secure by Letters Patent is:

In a chair for theaters, concert rooms or the like, having a seat and back automatically and positively rotatable together out of the position of use, an incandescent lamp arranged in the chair frame, the circuit of which is closed by a switch controlled by the movement of the said rotatable parts when turned out of the position of use, substantially as described.

In testimony whereof we affix our signatures, in presence of two witnesses.

ANDREAS FORSTER.
HANS WANEK.
